[57] CLAIM

The ornamental design for a card holder, as shown and described.

DESCRIPTION

FIG. 1 is a perspective view of a card holder showing my new design;

FIG. 2 is a front view thereof;

FIG. 3 is a rear view thereof;

FIG. 4 is a left side view thereof;

FIG. 5 is a right side view thereof;

FIG. 6 is a cross-sectional view thereof through section 6—6 of FIG. 5;

FIG. 7 is a top view thereof;

FIG. 8 is a bottom view thereof;

FIG. 9 is a perspective view of the base of the card holder shown with the clamp removed for convenience of illustration;

FIG. 10 is a front view of FIG. 9;

FIG. 11 is a rear view of FIG. 9;

FIG. 12 is a top view of FIG. 9;

FIG. 13 is a perspective view of the clamp member shown separately for convenience of illustration;

FIG. 14 is a front view of FIG. 13;

FIG. 15 is a rear view of FIG. 13;

FIG. 16 is a top view of FIG. 13;
FIG. 17 is a left side view of FIG. 13;
FIG. 18 is a right side view of FIG. 13; and,

FIG. 19 is a bottom plan view of FIG. 13.
